DESIGN FOR A LIGHTER FOR CIGARETTES OR THE LIKE

Luke J. Strauss, Buffalo, N. Y., assignor of one-half to Louis Buchmann

Application September 10, 1945, Serial No. 121,978

Term of patent 14 years

(CL. D48—27)

To all whom it may concern:

Be it known that I, Luke J. Strauss, a citizen of the United States, residing at Buffalo, in the county of Erie and State of New York, have invented a new, original, and ornamental Design for a Lighter for Cigarettes or the like, of which the following is a specification, reference being had to the accompanying drawing, forming part thereof.

Fig. 1 is a side elevation of a lighter for cigarettes showing my new design;

Fig. 2 is an end elevation thereof;
Fig. 3 is the other end elevation thereof;
Fig. 4 is a top plan thereof; and
Fig. 5 is a bottom plan thereof.

I claim:

The ornamental design for a lighter for cigarettes or the like, as shown.

LUKE J. STRAUSS.
